STRAINER FOR ROOF DRAINS, FLOOR SINKS AND THE LIKE

Douglas J. Cooper, Scottsdale, Ariz., assignor to Specialty
Sheet Metal Co., Phoenix, Ariz.

Filed Apr. 29, 1971, Ser. No. 138,861

Term of patent 14 years

Int. Cl. D23—01

U.S. Cl. D23—41

FIG. 2

FIG. 3

FIG. 4

FIG. 1 is an isometric view of a strainer for roof drains, floor sinks and the like showing my invention;

FIG. 2 is a side elevation of the same;

FIG. 3 is a top view of the same; and

FIG. 4 is a bottom view of the same.

I claim:

The ornamental design for a strainer for roof drains, floor sinks and the like, as shown.
